TETHERED BALL GAME BOARD

Donald Huffman, Montreal, Quebec, Canada, assignor to
Coleco Industries, Inc., Hartford, Conn.

Filed Sept. 9, 1971, Ser. No. 179,265

Term of patent 14 years

Int. Cl. D21—01

U.S. Cl. D34—5 BB

FIG. 1

FIG. 9

FIG.2

FIG.3

FIG. 4

FIG. 5

FIG. 8

FIG. 6

FIG. 7

FIG. 1 is a perspective view of a tethered ball game board showing my new design;

FIG. 2 is a plan view thereof;

FIG. 3 is a side elevational view of the game board;

FIG. 4 is a front elevational view of the game board;

FIG. 5 is a rear elevational view of the game board;

FIG. 6 is a bottom view of the game board;

FIG. 7 is a plan view of the game with the tethered ball supporting element rotated 180° from the position shown in FIGS. 1-6;

FIG. 8 is a front elevational view of the game board as illustrated in FIG. 7; and

FIG. 9 is a fragmentary side elevational view of the game board as illustrated in FIG. 7.

I claim:

The ornamental design for a tethered ball game board, as shown and described.
